OF MASSACHUSETTS.

SPINDLE.

Application filed October 3, 1923. Serial No. 666,293.

This invention relates to spindles of the character used particularly in the textile industry for spinning, twisting, and the like.

5 Spindles of this type are required to rotate at such high speeds that any imperfections in the balance of the spindle or its load, or in the lubrication of the spindle, adversely affect its running qualities.

10 The methods of manufacture of spindles have been so improved that, as a rule, the spindles alone run satisfactorily, but the spools or other thread bodies carried by the spindles often become warped, misshapen or chipped sufficiently to so unbalance the load 15 that the geometrical axis of rotation of the spindle does not pass through the center of gravity of the spindle plus its load. The pull of the belt or band by which the spindle is driven, and variations in the tension of the 20 yarn or thread which is being twisted or spun, also affect the running qualities of the ordinary spindle. Those skilled in this art are only too familiar with the violent chattering or vibration of the spindles of a spinning 25 frame when the spindles are coming up to speed. This chattering or vibration is most violent at what may be called a "critical speed" which, as a rule, is considerably below the running speed, so that when the spindles 30 have once reached their normal running speed they then run more satisfactorily. But during the period in which they pass through the critical speed, their violent vibration or chattering is objectionable, both from an operating standpoint, and also because it frequently results in breaking the strand of 35 material being twisted or spun, particularly if this strand is weak or delicate.

40 With these considerations in view, the present invention has for its chief object to devise a spindle structure which will overcome the difficulties above mentioned. It is a particular object of the invention to devise a spindle which will run steady even under 45 conditions that would cause spindles of the usual constructions to vibrate excessively, and to provide a spindle of this character which can be manufactured economically, in which wear and depreciation shall be reduced 50 to a minimum, and which generally will satisfy the practical requirements for a device of this type.

55 The nature of the invention will be readily understood from the following description when read in connection with the accompany-

ing drawings, and the novel features will be particularly pointed out in the appended claims.

In the drawings,

Figure 1 is a vertical, cross-sectional view 60 of a spindle structure embodying the invention in the form at present preferred;

Fig. 2 is a cross-sectional view through the central portion of the spindle, the plane of cross-section being at right angles to that in 65 Fig. 1;

Fig. 3 is a perspective view of one of the bearing members for supporting the bolster; and

Fig. 4 is a perspective view of part of a 70 sleeve which forms one element of the structure.

The construction shown, comprises a spindle blade 2 of a common form having a whirl 75 3 secured fast thereon. The blade is supported in a bolster 4 which carries two bearings for the blade. One of these bearings is of the step form and consists of a bronze block 5 secured in the bottom of the bolster by a pin 6, while the other consists of a bronze 80 bushing 7 which is frictionally held in the upper end of the bolster and supports the blade laterally. Between these two bearings, however, the blade is unsupported. The whirl is provided with a surface 8 to receive 85 the driving belt or band, and the center line of the pull of this band or belt is indicated by the line $x-x$, Fig. 1. It should be noted that the bearing bushing 7 supports the blade laterally in the general region of the line of belt 90 pull.

The bolster 4 is mounted within a spindle base, indicated in general at 10, and which comprises a central part designed to rest on a spindle rail 11, and upper and lower tubular extensions 12 and 14, respectively, that project above and below the rail 11, and which together form a housing for the bolster and its associated parts. The bolster is suspended within this housing on a ball and 95 socket bearing comprising a ball member 15 and a sleeve 16 having a socket formed in its upper end to receive the part 15. This part 15 is not a complete ball, but is, roughly speaking, hemispherical in shape, having 100 a flat upper surface, the plane of which, in the construction shown, lies just above the plane of the line of belt pull $x-x$. The center of the spherical surface of the part 15 preferably lies substantially in the line 110

x—x. A strong spring 17 is seated in a counter-bored section of the base and presses the socket member 16 firmly against its co-operating ball member 15. The upward movement of the latter member, however, is limited by a stationary sleeve 18 having, at its lower end, a flat annular face 19, Figs. 2 and 4, against which the upper flat face of the part 15 bears. A cap 20 is threaded on the upper end of the housing 12 and holds the sleeve 18 against upward movement, and thus, also, maintains the spring 17 under compression. This sleeve is prevented from rotating in the housing by means of a key 21 which fits in a keyway formed in the wall of the housing. The sleeve also has two holes or recesses 23, Fig. 4, formed in its lower end, either one of which may receive a pin 22 carried by the member 15 and which prevents the latter member from rotating.

It will now be understood that when this spindle is running and carrying a thread body, the weight of which is eccentrically disposed, this factor and the tension of the thread or yarn tends to tip the spindle and thus to produce the chattering or vibration which has been so objectionable in prior constructions. In the present arrangement such tipping of the spindle in any direction results in swinging the part 15 on the lower annular face 19 of the sleeve 18 as a fulcrum. This depresses the socket sleeve 16 against the tension of the spring 17. Such tipping movement, therefore, is yieldingly resisted by the spring, which acts through the ball and socket bearing to hold the spindle and the bolster normally in their central positions. While the spindle, therefore, can yield to forces tending to tip it, it does, nevertheless, oppose a resilient or elastic resistance to such forces, and tends to return to its central or normal position. We have definitely established that this spindle does operate satisfactorily under unbalanced loads and under running conditions which would make proper operation impossible with any other spindle of which we have been able to learn. The reasons for this improved result are somewhat obscure, but the following is the explanation which is supported by the data at present available: A spindle, whether of the construction here shown, or of the usual commercial constructions, is mounted for rotation about its geometrical axis. When such a spindle carries an eccentric or unbalanced load and is run at high speeds, it then tends to rotate, not about its geometrical axis, but about an axis passing through the center of gravity of the entire rotating mass. Consequently, when a spindle so loaded is started from a condition of rest and its speed of rotation is gradually increased, the forces tending to shift from the geometrical axis to the natural axis of rotation gradually increase. A con-

flict, therefore, is set up between the forces tending to maintain or establish these two axes, with the result that the spindle vibrates or chatters. If the spindle is rigidly supported, this conflict continues at practically all speeds and the spindle never runs steady. Usually, however, there is enough play in the spindle blade bearing to enable the axis of rotation to win the battle before the running speed is reached so that the spindle runs steady, or fairly so, at normal speeds. In the construction shown the spindle is so supported that it can tip freely, and the conflict therefore is won by the axis of rotation at a very low speed, or almost at the start, and the spindle runs steady at all higher speeds. In fact, no vibration is observable at any speed. At high speeds and with an unbalanced load this spindle has a gyrating motion. That is, it gyrates around an axis passing through the center of gravity of the entire rotating mass and the center of the ball member 15. The amplitude of gyration, of course, is very small so that, to the eye, the spindle appears simply to be rotating on a stationary axis and it runs perfectly steady.

The tension of the thread or yarn being spun appears to have no adverse effect on the running of this spindle. If the spindle can be said to have a "critical speed," this critical point is so low that the thread or yarn at this time is not subjected to any substantial tension. Breakage of a fine yarn or thread, therefore, which occurs so frequently as a spindle passes through its critical speed is practically eliminated with this construction.

Any tendency of the belt pull to tip the spindle is prevented by the centering of the ball and socket bearing substantially in the line of belt pull, it being understood that the belt moves up and down slightly over the surface 8 of the whirl so that the exact line of the belt pull is constantly shifting up and down through a very small distance.

The location of the flat annular meeting surfaces of the sleeve 18 and ball member 15 closely adjacent to the center of the ball, is of advantage in affording a maximum leverage for the force that is exerted by the spring 17 and which tends to hold the spindle and bolster in their central positions. Any rocking of the spindle under a force which tends to tip it violently is positively limited by the engagement of the lower end of the bolster with the inside wall of the housing 14, a clearance of, say, fifty-thousandths of an inch being provided between these parts. A clearness is provided between the parts 15 and 16 to permit their relative tipping movement, as is clearly shown in Fig. 2.

For the purpose of lubricating the bearing surfaces the base 10 is provided with

the usual oil spout 24, the upper end of which is closed by a hinged cover 25 that performs the double function of a cover and also of a latch to prevent any substantial upward movement of the whirl during dof-
5 fng. The oil spout opens into an oil well in the housing 14. Slots in the bolster 4 admit oil to the step bearing 5. When the spindle is running this oil travels upwardly 10 along the surface of the spindle through the bearing 7, and if permitted to do so, would climb up to the whirl and then work down to the skirt of the whirl and be thrown off in the form of a spray. In the present ar-
15 rangement this upward movement of the oil is limited by an oil ring 26 secured fast on the spindle at a point above the ball and socket bearing and above the upper end of the bushing 7. When the oil reaches this 20 ring, it is thrown outwardly against the inner surface of the sleeve 18 and drops into an annular pocket or well 27 formed between the bushing 7 and sleeve 18. An annular flange projects inwardly from the 25 lower end of the sleeve and forms the bottom of this well or pocket, and two holes 28—28, Fig. 2, are drilled through this flange to permit the oil to flow out of the pocket and on to the upper surface of the ball member 30 15. Two angular oil ducts 30—30, Fig. 2, conduct the oil from this surface to the top of the socket sleeve 16, and the oil flows around the upper edge of this sleeve and down through a split or cut 31, Fig. 3, in 35 the sleeve, into the oil well in the base 10. A complete circulation of oil thus is main-
tained, and all the friction surfaces, includ-
ing the flat contacting surfaces of the parts 15 and 18, and the spherical surfaces of the 40 ball and socket bearing are amply supplied with lubricant. A free movement of the parts in the manner above described thus is ensured at all times.

The split construction of the socket sleeve 16 is of advantage in giving this sleeve a certain amount of resiliency. The sleeve preferably is made so that it has a close but sliding fit with the inside of the housing, and the spring 17 pressing the sleeve firmly 45 against the ball surface 15 tends to expand the sleeve. Any wear which occurs between the friction surfaces of the ball and socket bearing thus is constantly taken up, while the tendency to expand the sleeve 16 also takes up wear between this part and the 50 housing 12.

It should be noted that this spindle structure is relatively simple, the various parts of the spindle structure can be manufactured economically, and, due to the efficient lubrication and the nature of the construction, wear and depreciation are reduced to a minimum.

While we have herein shown and de-
55 scribed the best embodiment of our inven-

tion that we have so far devised, it will be understood that the invention may be embodied in other forms without departing from its spirit or scope.

Having thus described our invention, 70 what we desire to claim as new is:

1. In a spindle, in combination, a bolster housing having a rail-engaging portion, a lower tubular portion extended below the rail-engaging portion for a substantial dis-
75 tance and closed at its lower end to form an oil well, and an upper tubular portion extended above the rail-engaging portion and open at its upper end, a bolster for the spindle blade in said housing, said bolster having its lower end extended below said rail-engaging portion into said oil well and laterally movable therein and provided at its upper end with a ball member and in-
80 sertible into and removable from said hous-
ing through the open upper end of said upper tubular portion, a socket member within the housing below the said ball member and slid-
85 able toward and from the latter, a spring in-
sertible into and removable from said hous-
ing through the open upper end of said tubular portion and initially compressed within the housing and surrounding the bolster below said socket member and acting on the latter to move it into engagement 90 with the ball member, and means for retain-
ing said spring in its initially compressed condition under normal conditions of use.

2. In a spindle, the combination of an upright spindle blade, a bolster in which said blade is mounted for rapid rotation, a whirl carried by said blade, a ball and socket bearing supporting said bolster in a suspended position and permitting the bolster to tip freely about a center located within said 100 whirl, a spindle base in which said bolster is mounted, the ball member of said bearing having a flat transverse face, another mem-
105 ber bearing against said face, and a spring 110 pressing said members together.

3. In a spindle, the combination of an up-
right spindle blade, a whirl carried by said blade, a bolster supporting said blade for rapid rotation, a ball and socket bearing on which said bolster is suspended, the upper surface of the ball member of said bearing being flat, a spindle base in which said bolster is mounted, a spring encircling said bolster and pressing the socket member of 115 said bearing upwardly against its cooperat-
ing ball member, and a stationary part against which the flat face of said ball mem-
ber is pressed by said spring.

4. In a spindle, the combination of a 120 spindle base, a bolster in which said blade is mounted for rapid rotation, a whirl carried by said blade and having a belt receiv-
ing face, a spindle base having a tubular housing in which said bolster is mounted, a ball and socket bearing supporting said bol-
125

ster in said base and enabling said bolster to tip about a center located within said whirl substantially in the line of pull of the driving belt for said whirl, the ball member of said bearing having a flat annular surface with the plane of said surface lying closely adjacent to said center, a spring mounted within said housing and pressing the socket member of said bearing against its cooperating ball member, and a stationary sleeve mounted within said housing and having a flat annular surface engaging the annular surface of said ball member.

5. In a spindle, the combination of a spindle blade, a bolster supporting said blade for rapid rotation, a whirl carried by said blade, a ball and socket bearing supporting said bolster in a suspended position, a spring within the housing below the ball and socket bearing, a sleeve within the housing above the ball and socket bearing and movable in said housing to move said ball and socket bearing within the housing and effect initial compression of said spring, and means cooperating with said sleeve and housing to retain said spring in its initially compressed condition.

6. In a spindle, the combination of a spindle blade, a whirl carried by said blade and having a surface to receive a driving belt, a spindle base having a part designed to rest on the ring rail of a spinning frame and having a tubular housing extending for a substantial distance both above and below said rail, a bolster mounted in said housing and having a step bearing near the bottom of the housing to support the lower end of

said blade and a guide bearing in line with the pull of said belt for laterally supporting the spindle, a ball and socket bearing suspending said bolster within said housing and permitting said bolster to tip about a center located substantially in the line of belt pull, said bearing including an approximately hemispherical ball member and a split socket sleeve in which said ball member is mounted, a coiled spring encircling said bolster and pressing said socket member against its cooperating bearing member, said ball member having a flat annular surface, the plane of which lies substantially in the line of pull of said belt, and a stationary sleeve mounted within said housing and having a flat annular surface against which the annular surface of said ball member is held by said spring.

7. In a spindle, the combination of a spindle blade, a bolster supporting said blade for rapid rotation, a whirl carried by said blade, a ball and socket bearing for supporting said bolster and enabling the bolster to tip about a center located within said whirl, a spindle base having a tubular housing in which said bolster is mounted, said bearing including a ball member and a split sleeve slidably mounted in said housing and having a socket to receive said ball member, and a spring holding said ball and sleeve firmly in engagement with each other.

In witness whereof we have hereunto signed our names to this specification.

EDWARD B. FEASTER.
ALBERT W. ARNOLD
